BOBBIN CARRIER

Ernest Johnson Eaddy, Spartanburg, S. C.

Application June 27, 1949, Serial No. 101,585

2 Claims. (Cl. 214—121)

1

This invention relates to bobbin carriers.

An object of this invention is to provide a carrier for bobbins wherein the bobbins may be transported from one machine to another and dumped from a basket or box into a bobbin bin.

Another object of this invention is to provide a carrier which includes a dumping cradle designed to receive a basket or box containing bobbins, the cradle being tiltable in a portable frame and including means for locking the basket or box therein.

A further object of this invention is to provide an improved means for rockably mounting a cradle in a portable frame so that the cradle may be shifted laterally of the frame during the tilting operation in order to assure discharge of the bobbins in the bin. The mounting means also includes means whereby the discharge side of the cradle is locked against downward and rearward movement until the cradle is disposed in substantially upright position.

With the above and other objects in view, my invention consists in the arrangement, combination and details of construction disclosed in the drawings and specification, and then more particularly pointed out in the appended claims.

In the drawings,

Figure 1 is a detail end elevation of a bobbin carrier constructed according to an embodiment of this invention, showing the basket cradle in tilted discharging position.

Figure 2 is a detail front elevation of the device.

Figure 3 is a sectional view taken on the line 3—3 of Figure 2.

Figure 4 is a longitudinal sectional view taken vertically through the device, showing the basket in partly extended position with respect to the cradle.

Figure 5 is a plan view of the device.

Figure 6 is a bottom plan view of the basket.

Figure 7 is a fragmentary plan view showing the box locking means carried by the cradle.

Figure 8 is a fragmentary sectional view taken on the line 8—8 of Figure 4.

Figure 9 is a fragmentary sectional view taken on the line 9—9 of Figure 2.

Figure 10 is a fragmentary sectional view taken on the line 10—10 of Figure 1.

Figure 11 is a fragmentary sectional view taken on the line 11—11 of Figure 10.

Figure 12 is a fragmentary end elevation, partly in section, of the upper portion of the mobile frame.

Referring to the drawings, the numeral 15 designates generally a mobile frame which includes a lower rectangular frame 16 having end castor wheels 17 mounted thereon, and intermediate wheels 18. The frame 16 has secured to the rear thereof a pair of upright angle-shaped frame members 19 and a pair of U-shaped channel

members 20 are secured to the front portion of the frame with the channels thereof in confronting position.

The channel members 20 comprise guides for the cradle to be hereinafter described, and upper angle frame members 21 extend vertically upwardly from the guides 20 and are connected to the rear uprights 19 by upper end angle members 22. The end members 19 are connected together by an upper horizontal connecting bar 23 and the front angle members 21 are connected together by an angle-shaped connecting bar 24.

The guides 20 have extending forwardly from the upper ends thereof upper horizontal guides 25, the purpose for which will be hereinafter described. A cradle generally designated as 26 is disposed in the frame structure 15 and comprises a U-shaped member which is open at each end. The cradle 26 is formed of U-shaped end members 27 connected together by lower connecting bars 28, and upper connecting bars 29 and 30.

A guide rail 31 is connected between the uprights 32 at the front of the cradle 26 so as to prevent the lower portion of the basket 33 from slipping downwardly and outwardly from the cradle at the time the latter is tilted to discharge the bobbins disposed in the basket 33.

The frame 15 has mounted adjacent each end thereof rollers 34 over which the runners 35 at the bottom of the basket 33 are adapted to movably engage. The cradle 26 is also provided with transversely extending rollers 36 which are in substantially the same plane as the rollers 34 so that the basket 33 can be readily moved onto the cradle when the basket is in a filled position.

The basket 33 is adapted to be locked at its rear portion by means of L-shaped locking members 37 which are secured to a shaft 38 rotatably carried by the upper rear portion of the cradle 26. The locking members 37 are engageable over the rim of the basket 33 at the rear thereof, and the locking members 37 are fixed in locked position by means of a locking bar 39 pivotally mounted on a pivot 40 carried by one end of the cradle 26. When the locking member 39 is swung in a clockwise direction, as viewed in Figure 5, this locking member will overlie an adjacent basket locking or clamping member 37.

The cradle 26 has secured to the front uprights 41 thereof upper rollers 42 which engage in the guide members 20, and each upright 41 has secured thereto a lower roller 43 engageable in a guide channel 20 and movable out of the channel 20 through an opening 44. When the upper roller 42 is moved forwardly by means of a curved guide 45 positioned at the upper end of the upright channel 20 and is then moved forwardly into the horizontal channel 25, the roller 43 will swing rearwardly and upwardly through the opening 44.

The cradle 26 is tilted from an upright re-

ceiving position to a tilted discharging position by means of a pair of cables 46 which are secured at their lower ends, as at 41, to the cradle 26 and are wound about a pair of winding drums 48 mounted on the winding shaft 49. The shaft 49 is journalled in bearings 50 carried by the top frame bars 22, and the shaft 49 at one end thereof has secured thereto a sprocket 51 about which a chain 52 engages. The chain 52 extends downwardly and rearwardly and is trained about a lower small sprocket 53 which is secured to a crankshaft 54. A crank 55 is carried by the crankshaft 54 and is disposed outwardly of a housing or shield 56 engaging about the chain 52.

The shaft 49 has secured thereto a ratchet wheel 57 with which a spring-pressed pawl 58 engages, the pawl 58 being rockably carried by a pivot 59 which engages through an ear 60 carried by the adjacent upper frame bar 22. The pawl 58 is constantly urged to latching position by means of a spring 61.

In order to provide a means whereby the cradle 26 will not be permitted to drop downward when in a tilted or discharging position, by rearward movement of the rollers 42 in the horizontal channels 25, I have provided locking rollers or pins 62 which are carried by the uprights 41 and are movable in the channels 20 and 25.

In the use and operation of this device, the basket 33 is initially filled with bobbins which are to be discharged into a receiving bin B. The basket 33 is rolled into the cradle 26 and locked therein by the locking members 37. The frame 15 is then moved to the front of the bin B and the cradle 26 may be raised to a tilted discharging position by turning the crank 55. The cables 46 will raise the cradle 26, the lower rollers 43 initially preventing the tilting of the cradle until the upper rollers 42 pass into the rear ends of the horizontal channels 25. When the upper rollers 42 are in the rear ends of the upper channels 25, the lower rollers 43 will be in alignment with the openings 44 of the upright channels 20 so that the further winding of the winding shaft 49 will cause the cradle 26 to tilt upwardly at its rear side. The cradle 26 may be tilted to the desired degree which may be either in a horizontal position slightly above or below the horizontal, depending upon the number of bobbins which are to be discharged into the bin B.

When the cradle 26 is to be lowered, the pawl member 58 is released from the ratchet 57 and the crank 55 is rotated in an unwinding direction. When the rear end of cradle 26 swings downwardly with upper rollers 42 as fulcrums, intermediate rollers 62 will swing downwardly into channels 20 and will strike the front walls of channels 20 forming intermediate fulcrums for front bars 24 so that at the time rollers 43 are entering openings 44 rollers 42 will be moving rearwardly in horizontal channels 25. When rollers 43 are entirely within channels 20 the front bars 24 of cradle 26 will be very close to vertical and rollers 42 will be at the inner ends of upper channels 25 so that rollers 42 may readily enter the upper ends of channels 20. At this time the rollers 42 will be entering the upper end of the channels 20 so that further unwinding of the shaft 49 will permit the cradle to drop vertically downward. This carrier will permit the rapid and easy discharge of bobbins from a basket or box, and due to the horizontal channels 25 and the locking members 62 the carrier or cradle 26 will be prevented from dropping down-

wardly at its forward side until the cradle is in an upright position.

I do not mean to confine myself to the exact details of construction herein disclosed, but claim all variations falling within the purview of the appended claims.

What I claim is:

1. A wheeled carrier for bobbins comprising a mobile frame, a basket cradle of U-shape in said frame, a pair of confronting channel shaped vertical guides at the forward side of said frame, a horizontal forwardly extending guide extension at the upper end of each vertical guide, a pair of vertically spaced apart rollers carried by each end of said cradle engaging in said vertical guide when said cradle is in a lower receiving position, an intermediate roller carried by said cradle between said pair of rollers engaging in said vertical guides for holding said cradle against rearward movement when said cradle is in a tilted position and for effecting rearward movement of the upper one of said pair of rollers when said cradle is swung downwardly from a tilted to a vertical position, means engaging the lower rear portion of said cradle for raising, lowering, and tilting the latter, each of said vertical guides having an opening in the inner side thereof upwardly from the lower end whereby the lower roller of said pair of rollers may pass out of the vertical guide at the time the upper one of said rollers is entering the horizontal extension to thereby provide for tilting of said cradle.

2. A wheeled carrier for bobbins comprising a mobile frame, a basket cradle of U-shape in said frame, a pair of vertical guides at the forward side of said frame, a horizontal forwardly extending guide extension at the upper end of each vertical guide, a roller carried by each end of said cradle engaging in said vertical guide when said cradle is in a lower receiving position and engaging in said guide extension when said cradle is in an upper tilted position, means for locking a basket in said cradle, a lower roller carried by each end of said cradle engaging in said vertical guide, an intermediate roller carried by each end of said cradle engaging in said vertical guide, each guide having an opening in the inner side thereof above the lower end thereof, and means engaging the lower rear portion of said cradle for tilting the latter said lower roller passing rearwardly through said opening at the time said first named roller is entering said horizontal guide whereby said cradle will be tilted by further upward movement thereof, said intermediate roller constituting means whereby during the downward movement of said cradle, said first named roller will be held against rearward movement in said horizontal extension without downward swinging of said cradle to an upright position.
